ROOF CONSTRUCTION

George E. Swenson, Hastings on Hudson, N. Y.,
and Emile Frederick, Jr., New Orleans, La., as-
signors to The Celotex Corporation, Chicago,
Ill., a corporation of Delaware

Application December 24, 1937, Serial No. 181,474

19 Claims. (Cl. 108—6)

In the construction of roofs for various structures, it has in the past been extremely difficult to provide a roof structure which includes thermal insulation positioned particularly on the top 5 surface of the roof structure which functions satisfactorily. There are various reasons for the unsatisfactory results obtained with the various such constructions that have heretofore been used among which defects probably the principal 10 item has been that roofing surfaces laid over such insulated roof constructions have a decided tendency to blister, that is, for the roofing to loosen in spots and be raised as a distinct blister and in fact over various of such roof structures 15 such blistering has at times been of sufficient extent that substantially the entire roof covering has been loosened from the underlying portions of the structure.

The difficulties encountered have been particularly severe where such constructions have involved concrete roof decks although such difficulties are from time to time met in substantially all types of roof construction which involve the use of an insulating material having laid 25 thereover saturated and coated roofing felts.

The loosening of the roof surfacing sheet in such roof structures appears to be due to the fact that the roofing sheet is laid on the thermal insulating material adhered thereto with asphalt, pitch, or like binding substance, which substances at temperatures around, say, 120 degrees Fahrenheit, which are commonly encountered on roofs in the summer time, soften and have no substantial internal strength so that a relatively 30 slight force tending to part the roof sheet from the insulating sheet will readily cause separation due to such softened condition of the adhesive.

If, with the adhesive material securing the insulating sheet and the roofing sheet in a softened 40 condition, either a slight air pressure or water vapor pressure, or a combination of the two, is exerted within the roof structure, it results that the roofing sheet is separated from the insulation sheet and the blisters previously referred to are 45 formed.

The usual roof structure is one wherein the roof comprises a concrete slab, deck or the like, which in the construction, serves on the underside of the roof structure as an air impervious 50 barr'er which will prevent the escape of air downwardly. On this concrete roof slab there is installed a thermal-insulating material such as for example, a fiber insulating board, which insulation is usually secured to the upper surface of 55 the concrete slab by a hot mopping of asphalt,

or pitch, or the like, in which the insulation sheets are bedded. There is applied over the insulation sheets saturated and coated felt roofing or the like, which is mopped down to the upper surface of the insulation board with asphalt, pitch, 5 or the like, which felt roofing when properly applied comprises a water and substantially air impervious top cover for the entire construction.

Thermal insulation is ordinarily obtained by the use of materials which are relatively light 10 and porous or cellular so that an appreciable portion thereof comprises cells, channels, or the like, which are normally more or less closed air chambers in which the enclosed air is in fact the insulating medium. Still air, that is, air which 15 is not free to freely circulate is one of the best thermal insulators known and its properties are availed of in manufacturing thermal insulating materials as above pointed out.

The fact that thermal insulating materials contain a relatively large amount of air is detrimental in the construction of a roof structure comprising the various elements as above pointed out in that this air contained in the insulating material expands very considerably when the 20 roof structure is heated as in the summer time, and this creates a definite pressure within the structure between the air impervious roof deck and the air impervious roofing felt covering. Such air pressure developed within the structure 25 is sufficient to break the bond of the asphalt, or like adhesive, by means of which the roofing felt is adhered to the surface of the insulating material and it results that the roofing felt is raised, at least in places, from the insulating material 30 and the so-called blisters are formed. In addition to the pressure created by the expansion of air in the composite roof structure, this condition is probably accentuated due to the fact that the thermal insulation normally contains a certain 35 amount of water and water vapor due to the fact that substantially all of the commercial thermal insulating materials are of a character which under normal conditions contain absorbed moisture to the extent of at least about 8% by weight 40 and in addition to this absorbed moisture the air enclosed within the cellular structure of the insulating material carries therewith water vapor in an amount in accordance with the vapor tension existing under the from time to time existing 45 temperatures. This moisture contained in the thermal insulating material when heated, say, to 120 degrees Fahrenheit, which is common on roofs in the summer time, is more or less vaporized and the roof structure is subjected to the 50 55

effect of the combined pressures of the expanded contained air and vaporized moisture.

The object of this invention is to provide a roof construction wherein there is prevented from being built up within the structure a pressure greater than atmospheric pressure so that there is no tendency for the roof covering sheet, that is, the saturated roofing felt, to be lifted from the thermal insulating material to which it is adhered, and incidental to such principal objects of the invention there are involved the objects of providing a generally improved roof construction which does not involve complications in its application but which will overcome the principal objections to the use of thermal insulation embodied in the roof structure directly under the roofing felt surfacing sheet.

The invention is illustrated in the accompanying drawings wherein Figure 1 is a cross-section 20 of a portion of a roof structure, Figure 1A is a detail of a modification of the structure shown in Figure 1, Figure 2 is a worm's eye perspective of the construction illustrated in Figure 1 with a portion broken away, Figure 3 is a section of Figure 1 taken on line 3—3, Figure 4 is a fragmentary section of the roof illustrating a vapor escape means, Figure 5 is a view similar to Figure 4 but showing a modified form of the construction, Figure 6 is a detail of a thermal insulating unit 25 with portions broken away, Figure 7 is a fragmentary elevation of a modified thermal insulating unit, Figure 8 is a fragmentary elevation of a further modified form of the thermal insulating unit, and Figure 9 is a fragmentary perspective of a still further modification of the thermal insulating unit.

Attention is directed to the fact that while the inventions hereof are generally applicable in a construction including any form of roof deck, 40 it is of particular value in connection with these forms of roof deck wherein the roof deck is a tight structure, that is, one which will not allow air to pass downwardly through the roof deck, and that the invention is particularly applicable 45 to a roof deck comprising a concrete or like continuous slab construction, or to any deck to which a continuous vapor-seal is applied before the insulation is laid.

In the roof construction illustrated in the accompanying drawings, a roof deck is indicated at 50 10, such roof deck being shown as a concrete slab but which deck, of course, may be any other usual form of roof deck.

In connection with the roof slab 10 there is 55 indicated the usual parapet wall 11 and over the slab 10 there are shown applied thermal insulating units 12. The thermal insulating units 12 may be and preferably are sheets of fiber insulating board such as are regularly available although in accordance with the invention hereof, 60 these sheets are specially prepared as hereinafter described, or instead of comprising sheets of fiber insulation board, the thermal insulation units may be formed of any desired material which will 65 provide the requisite insulation.

The thermal insulating sheets 12 are preferably adhered to the roof deck 10 by mopping the roof deck with hot asphalt whereupon the thermal insulating units 12 are applied to such mopping 70 of hot asphalt before it is cooled so that upon cooling the units 12 are securely adhered to the surface of the slab 10. Units 12 may be of any practical dimensions and preferably they are about 22" x 47" and have a thickness of $\frac{1}{2}$ ", 75 1", $1\frac{1}{2}$ ", or such other thickness as is deter-

mined to be the economical thickness of thermal insulation for use in the particular structure.

The thermal insulation units 12 are formed so that when a plurality of these units are laid in juxtaposition, there are formed intersecting channels comprising a continuous channel network 17 through the thermal insulating material.

The continuous net work of channels 17 may be formed in any desired way but the preferred 10 manner in which these are provided is through forming the thermal insulating units as is shown in Figure 6, in which the unit is shown, around its edges on its underside, as rabbeted with an inclined wall as at 14 whereby when a plurality 15 of such units are laid in adjacent relationship there is formed along such meeting edge a channel such as is shown at 17 in Figures 1 and 2. A modified form of rabbeting the edge of units 12 is shown in Figure 7 wherein the lower part of the 20 unit is rabbeted with a vertical face 15 and a further modified manner for providing the channel net work is shown in Figure 8 wherein the unit 12 is provided around its edges with a V-groove indicated at 16. Any one of the several 25 forms of units illustrated in Figures 6, 7 and 8 will provide the continuous net work of channels 17 and it is readily evident that such channels may be provided by any one of many other 30 forms of channeling, etc., of the units 12, as by grooves or channels provided on the under side, not at the edges, if properly aligned with adjacent units.

The units 12 having been applied to roof deck 35 10 in accordance with the previously described procedure, a roofing material which may be the ordinary saturated and coated felt roll roofing 23 is applied over the surface of units 12 in accordance with usual practices, that is, successive 40 widths of the saturated roofing material are mopped over the surface of units 12, adhered with asphalt, or the like, with succeeding widths of such saturated roofing overlapped and adhered to one another as is usual practice.

The usual flashings 24 are applied at the edges of the roofing 23 which has been laid in accordance with the above description with one edge sealed to the roofing 23 and with the upper ends of such flashings extending into parapet wall 11 50 and appropriately sealed thereagainst in accordance with usual practices. Flashing 24 is provided with slits or openings 25 which is a feature differing from usual practice and further, the flashing is so applied that at and in the vicinity 55 of such slits, the vertical portion of such flashings, that is, the portion extending from the roof surface to the parapet wall, is not adhered solidly to the parapet wall. Over the usual flashing 24 there is applied a secondary protecting flashing 60 which is appropriately secured to parapet wall 11 and extends down over the vertical portion of the usual flashing 24 to cover the slits 25 but such secondary flashing 26 is not adhered to the usual flashing 24 nor preferably does it extend 65 completely down to the surface of the roofing 23. This secondary flashing 26 is merely a protective flashing to prevent water, that is, rain, snow, or the like, from being driven into the openings 25 and this flashing need not be continuous 70 but may be applied as short sections only of sufficient width to protect the openings 25 in the flashing 24.

The openings 25 in flashings 24 serve as escape channels for air and vapor coming from the 75

channel net work 17 and their action in this respect is as follows:

A roof structure as above described, that is, with an air impervious base such as the slab 10 having the thermal insulating material 12 applied thereto with an air impervious roof covering 23 applied thereover, constitutes, together with the flashings and parapet wall, and the like, a completely closed system in which there is trapped a certain amount of air and moisture, this being primarily the air contained in the thermal insulating units 12 and the moisture contained in such units and in the slab 10. Such a roof system as it heats up under the action of the sun in the summer time will rise to a temperature which may readily be 120 degrees Fahrenheit and even higher in extremely hot weather, and when this happens the air trapped therein expands in accordance with such temperature to create a positive pressure exerted between the slab 10 and the roof covering 23. In addition to the pressure created through the expansion of the trapped air, moisture which is within the system is vaporized in accordance with the temperature and pressure prevailing, that is, a certain amount of the moisture vaporizes in accordance with the vapor tension of water under the conditions of tension and pressure prevailing, and therefore there is present, within the closed system which has been described, a composite gas which is made up in part of air and in part of water vapor, which composite gas has a pressure corresponding to the temperature prevailing.

The pressure of the gas within the closed system tends to, due to the fact that the slab 10 is impervious, exert a pressure upon the roofing sheet 23, particularly due to the fact that the asphalt with which such sheet is ordinarily applied to the insulating material 12 softens at elevated temperatures and has under such conditions little or no internal strength, causing the surface sheet 23 to pull away from the surface of the insulation 12 and to form distinct blisters raised from the normal plane of the roof.

Due to the fact that the composite roof structure hereof is supplied with the net work channels 17, the gases in all portions of such structure are free to flow from one portion thereof to another, and it results that as the pressure within the structure tends to increase due to elevation of temperature, the expanded gases tend to flow through the channels 17 until eventually at the edges these expanded gases will escape up behind flashing 24 and out through openings 25 which are provided in the flashings. Thus the pressure within the system is relieved and there is not the tendency for the roofing 23 to be raised from the surface of the insulation 12.

A modified form of the construction shown in Figure 1 is shown in Figure 1A. This modified form shown in Figure 1A is in effect the addition of a check valve to the construction previously described. The construction shown in Figure 1A is substantially the same as that shown in Figure 1 except that insulation sheets 12 and roofing 23 are installed so as to terminate a short distance, say one to two inches from the parapet wall 11 and the space thus provided is filled with low melting point asphalt or pitch or the like as indicated at 27. This strip of asphalt 27 around the edge of the roof acts as a non-return valve.

As the roof structure heats up under the summer sun causing expansion of the gases and vapors within the system, the heat causes low melting point asphalt 27 to soften. As the gases and

vapors within the system heat up, they tend to expand and as soon as a slight pressure builds up within the roof system it is relieved by bubbling up through softened asphalt 27 to escape up behind flashing 24 and out of slit 25 therein, 5 to atmosphere.

As the roof system cools the gases and vapors therein tend to contract and atmospheric air would be drawn conversely into the roof structure but in cooling the asphalt 27 will have solidified and will prevent this from occurring and thus the effect of a non-return valve on the escape system is achieved.

In large roof areas, it is advisable that additional vents for the escape of excess pressure be provided, which vents may be supplied as illustrated in Figure 4 or 5 and which may be installed in such number as may be required to provide for the necessary relief of pressure from the interior of the system to prevent the loosening of roofing sheet 23 from the surface of the insulation as has been hereinbefore described. The additional vents may be supplied in such number as is deemed desirable and it is suggested that at least one of such be supplied for each 5,000 square feet of roof surface, although this is not a fixed matter since the requirement with respect to additional vents depends almost entirely upon the dimensions of the individual channels 17, that is, if the rabbeting or the like 20 of the individual sheets 12 is such that the dimensions of the channels will be small, the number of additional vents should be increased, whereas if the dimensions of the individual channels are relatively large, few, if any, additional 25 vents will be required.

The simplest manner of venting the structure is to provide a vent such as is disclosed in Figure 4 wherein there is shown merely a tube 18 inserted through the roofing sheet 12 and opening 40 into channel 17, the upper end of this tubing being bent into an inverted U shape so that rain or the like cannot readily get into the open end of the tube. The tube, of course, will be suitably flashed where it passes through the roofing sheet 45 23, such flashing being indicated at 19.

The vents 25, as above described, as well as 18, each provide for free flow of gases into and out of the channel system, that is, if the roof system heats up, the gases may flow out through 50 vents 25 and 18 and conversely as the roof structure cools down with the corresponding tendency of a vacuum occurring within the channel system 17, atmospheric air from the exterior will tend to be drawn into the channel system. Of course non-return valves, not shown, may be applied to vent tube 18. Such construction presents certain disadvantages in that atmospheric air drawn into the channel system will contain an amount of water in the form of water vapor 55 and under conditions which are well understood, that is, upon further cooling of the roof structure, it is quite probable that a certain amount of this water vapor will be condensed into water and thereby become present as water in the roof 60 structure. The presence of water, of course, within the composite roof structure is detrimental in that water as such, particularly should it eventually become present in sufficient amounts, will bring about deterioration of the structure and 65 in addition, the presence of water decreases the efficiency of the insulation.

In lieu of providing the relief vents either in the form of slits 25 in the flashings 24 or as open tubes 18 as disclosed in Figure 4, the vents may 70 75

be provided in the form as shown in Figure 5 wherein a vent pipe 18 is provided which extends through the roofing sheet 23 with its open end opening into channel system 17 and flashed as at 19. This tube 18, instead of being left open at its upper end, is provided with a collapsible airtight bag 20, or alternatively while not shown but as may be readily understood, it may connect with any other type of container which would correspond substantially to the airtight bag 20, but such container it is, of course, understood, would be sealed so that air could not flow in and out of the container except through tube 18 and constructed so that its volume expands and contracts 15 to compensate for the expansion and contraction of the volume of gases within the roof system without causing appreciable change in pressure, that is, constructed similarly to a gasometer. Collapsible bag 20, secured to the upper end of 20 tube 18 provides an enclosure into which, as may be readily understood, expanded gases from the channel system 17 may escape and from which, as the gases again contract upon cooling, they may be drawn back into the channel system so 25 that at no time is there any noticeable pressure built up within the roof system nor will it be subjected to any noticeable vacuum since upon tendency for either to occur, the excess air or vapor may escape either into the bag or be withdrawn therefrom.

The individual fiber insulation units 12 are preferably isolated one from another as by being coated with asphalt or the like as is indicated in Figure 6 wherein the unit 12 is shown as having 35 an asphalt or like coating 13 applied thereto, applied preferably by first dipping the unit in a low melting point asphalt which will penetrate the surface to at least a limited extent as is indicated by the dotted portions in Figure 6, after 40 which the unit is immersed in a relatively high melting point asphalt to cause a surface coating to be adhered to the surface of the unit, which surface coating will better adhere because of the initial penetration of the surface with the low 45 melting point asphalt as described. This provision of a sealed unit 12 in accordance with the description thereof just given provides such units so isolated, that should a leak occur in the roof structure there is little or no tendency for the 50 moisture to penetrate into the individual units 12 and, therefore, the detrimental effects of the presence of water in the units will not make itself apparent, and furthermore, should in some manner the water penetrate into one unit then due 55 to the fact that such unit is substantially sealed off from the other units, this moisture will not be distributed to a plurality of the units but will be retained in the individual unit which has been damaged to the extent that the water has been 60 enabled to penetrate thereto.

In lieu of a surface saturation and coating of the unit 12 with asphalt as above described, the unit may be enveloped in a water impervious membrane such as indicated at 27 in Figure 9 65 wherein 27 illustrates a water impervious membrane which has been wrapped around the unit 12 and is preferably secured thereto by a layer of asphalt, or the like, adhering membrane 27 to the surfaces of unit 12. This membrane 27 70 may be either a water impervious saturated felt or it may be a duplex paper, that is, two-ply paper plied with a continuous film of asphalt or the like, or it may be any other suitable water impervious membrane.

75 Such envelope enclosing insulation unit 12, if

membrane 27 is air and vapor proof, should have several small perforations such as 28 venting the enveloped unit to channel system 17 so that pressure may be relieved from within the envelope.

There having been above disclosed in its preferred embodiment and in detail a composite roof construction which embodies a provision for preventing the building up of air pressure between the roof slab and the roofing material and one wherein the construction is novel and useful, we 10 claim:

1. A composite roof structure comprising a roof deck, a layer of thermal insulation material comprising a plurality of insulating units on said deck and a finishing roofing material over said layer 15 of thermal insulation material, the thermal insulation material having extending throughout the layer horizontally thereof a communicating net work of interconnected passages, and said interconnecting passages formed by the juxtaposition of said insulating units.

2. A composite roof structure comprising a roof deck, a layer of thermal insulation material comprising a plurality of insulating units on said deck and a finishing roofing material over said 25 layer of thermal insulation material, the thermal insulation material having extending throughout the layer horizontally thereof a communicating net work of interconnected passages, the such net work of communicating interconnected passages 30 vented to the exterior of such composite structure, and said network of communicating interconnected passages formed by the juxtaposition of said insulating units.

3. A composite roof structure comprising a roof deck, a layer of thermal insulation material comprising a plurality of insulating units on said deck and a finishing roofing material over said layer of thermal insulation material, the thermal insulation material having extending throughout 40 the layer horizontally thereof a communicating net work of interconnected passages, said communicating network of interconnected passages formed by the juxtaposition of said insulating units, there being provided escape channels forming a means of communication from the net work of communicating passages to the exterior of the composite roof structure.

4. A composite roof structure comprising a substantially air tight roof deck, a thermal insulation course secured thereon, such thermal insulation course comprising a plurality of units, each unit enveloped in a waterproof enrolement and each unit recessed around its periphery, the such recesses in an assemblage of applied units cooperating and forming an intercommunicating net work of connected passages throughout the area of the thermal insulation course, a substantially airtight weather resistant roof surfacing material secured on the upper surface of the thermal insulation course, and a vent venting the net work of communicating passages to the exterior of the composite roof structure.

5. A composite roof structure comprising a substantially airtight roof deck, a thermal insulation course secured thereon, such thermal insulation course comprising a plurality of units, each unit enveloped in a waterproof enrolement and each unit recessed around its periphery, the such recesses in an assemblage of applied units 65 cooperating and forming an intercommunicating net work of connected passages throughout the area of the thermal insulation course, a substantially airtight weather resistant roof surfacing material secured on the upper surface of the ther- 70 75

mal insulation course, and a closed chamber in communication with the net work of communicating passages.

6. A composite roof structure comprising a substantially airtight roof deck, a thermal insulation course secured thereon, such thermal insulation course comprising a plurality of units, each unit enveloped in a waterproof enrobing and each unit recessed around its periphery, the such recesses in an assemblage of applied units cooperating and forming an intercommunicating net work of connected passages throughout the area of the thermal insulation course, a substantially airtight weather resistant roof surfacing material secured on the upper surface of the thermal insulation course, an extensible airtight container positioned adjacent the roof structure, and a venting passage connecting the airtight container and the net work of communicating passages.

7. A composite roof structure comprising a roof deck, a thermal insulation course thereon comprising a plurality of insulating units, and a substantially airtight roof surfacing material thereover, an air conveying passage extending throughout the area of such roof structure and serving to equalize gaseous pressure throughout such roof structure, said air conveying passage formed by the juxtaposition of said insulating units, and a connection from said air conveying passage to the exterior of said composite roof structure.

8. An insulated roof construction comprising a structure having a roof deck, parapet walls around the roof deck, a course of thermal insulation secured on the roof deck, a continuous weather resistant roofing secured on the upper surface of the thermal insulation course, the thermal insulation course having therethrough a system of communicating passageways, flashing secured around the edge of the roofing to its upper surface and sealed to the parapet wall, the flashing having therein vents, the vents in communication with the system of communicating passageways, and a secondary protective flashing secured to overhang the vents.

9. A composite roof structure comprising a roof deck, a thermal insulation course thereon, and a substantially airtight roofing thereover, air conveying passages which within said roof structure serve to substantially equalize gaseous pressure therethrough, the composite roof structure having a confining wall around its periphery but spaced from the periphery of the insulating course, and low melting point asphalt in the space between the periphery of the insulation course and the confining wall.

10. A composite roof structure comprising a substantially air-tight roof deck, a thermal insulation course secured thereon, the thermal insulation material having extending throughout the layer horizontally thereof a communicating network of interconnected passages, and a chamber connected to said network of interconnected passages and adapted to expand and contract, whereby the air pressure within said network is equalized.

11. A composite roof structure comprising a substantially air-tight roof deck, a thermal insulation course secured thereon, the thermal insulation material having extending throughout the layer horizontally thereof a communicating network of interconnected passages, and an extensible air-tight container connected to said net-

work of interconnected passages, whereby the air pressure within said network is equalized.

12. A composite roof structure comprising a roof deck, a thermal insulation course thereon, and a substantially air-tight roofing thereover, air conveying passages which within said roof structure serve to substantially equalize gaseous pressure therethrough, and means adapted for releasing the air pressure within the air conveying passages but preventing atmospheric air from returning thereto.

13. A composite roof structure comprising a roof deck, a thermal insulation course thereon, and a substantially air-tight roofing thereover, air conveying passages which within said roof structure serve to substantially equalize gaseous pressure therethrough, and self-sealing means adapted for releasing the air pressure within the air conveying passages but preventing atmospheric air from returning thereto.

14. A composite roof structure comprising a roof deck, a thermal insulation course thereon, and a substantially air-tight roofing thereover, air conveying passages which within said roof structure serve to substantially equalize gaseous pressure therethrough, and self-sealing means adapted for releasing the air pressure within the air conveying passages but preventing atmospheric air from returning thereto, said self-sealing means comprising a substantially low melting point fluent material.

15. A flashing construction adapted for a composite roof structure having air communicating passages throughout, comprising venting means for said air communicating passages, and said venting means adapted to communicate with the aforesaid air communicating passages and the atmosphere.

16. A thermal insulating unit adapted for assembly in a composite roof structure, and said unit recessed about its periphery; whereby, when said unit is assembled in a composite roof structure, a communicating network of interconnecting passages is formed for venting said composite roof structure.

17. A composite roof structure comprising a plurality of thermal insulating units, each of said units recessed about its periphery and adapted when assembled in juxtaposition to each other to form a communicating network of interconnecting passages for venting said composite roof structure.

18. A composite roof structure comprising a plurality of thermal insulating units, each of said units being waterproofed, said units adapted when assembled in juxtaposition to each other to form a communicating network of interconnecting passages for venting said roof structure, and each waterproof unit disposed within a waterproof pocket formed by adjacent units; whereby, if moisture enters a damaged unit, it is not transmitted to adjacent units.

19. A composite roof structure comprising a plurality of thermal insulating units, each of said units enveloped in a water impervious membrane, each of said units recessed about its periphery and adapted when assembled in juxtaposition to each other to form a communicating network of interconnecting passages for venting said composite roof structure, and means provided for each unit enveloped in a water impervious membrane for venting the interior thereof to the communicating network.

GEORGE E. SWENSON.
EMILE FREDERICK, JR. 75
